[57] CLAIM

The ornamental design for a convertible scooter-/wagon, as shown and described.

DESCRIPTION

FIG. 1 is a side elevational view of a convertible scooter/wagon in the wagon condition showing my new design, the side opposite being a mirror image;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof in its scooter condition;

FIG. 7 is a top plan view thereof in the scooter condition;

FIG. 8 is a front elevational view thereof in the scooter condition; and,

FIG. 9 is an enlarged cross-sectional view taken through FIG. 7 along the line 9—9.

*Fig.2.**Fig.1.**Fig.3.**Fig.4.**Fig.5.**Fig. 7.**Fig. 6.**Fig. 8.*
